DESIGN FOR A CHILD'S HANDKERCHIEF

Leah P. Kampner, Houston, Tex.

Application June 17, 1948, Serial No. 147,023

Term of patent 7 years

(Cl. D3—12)

To all whom it may concern:

Be it known that I, Leah P. Kampner, a citizen of the United States, residing at Houston, in the county of Harris and State of Texas, have invented a new, original and ornamental Design for Child's Handkerchief, of which the following is a specification, reference being had to the accompanying drawing, forming part thereof.

The figure is a plan view of a child's handkerchief, showing my new design.

I claim:

The ornamental design for a child's handkerchief, as shown.

LEAH P. KAMPNER.
